US0D1026298S

(12) **United States Design Patent** (10) **Patent No.:** **US D1,026,298 S**
(45) **Date of Patent:** **** May 7, 2024**

(54) **CRYSTAL SOLAR LIGHT**

(71) Applicant: **E. MISHAN & SONS, INC.**, New York, NY (US)

(72) Inventor: **Steven Mishan**, New York, NY (US)

(73) Assignee: **E. MISHAN & SONS, INC.**, New York, NY (US)

(**) Term: **15 Years**

(21) Appl. No.: **29/883,714**

(22) Filed: **Feb. 2, 2023**

(51) LOC (14) Cl. **26-05**

(52) U.S. Cl.

USPC **D26/87**; D26/67

(58) **Field of Classification Search**

USPC D26/65, 93, 138, 140, 141, 142, 22, 67, D26/72, 85, 87, 88, 89, 91, 92, 104, 110, D26/118, 120, 122, 123, 124, 128, 130, D26/135, 145; D11/89, 90

(57) **CLAIM**

The ornamental design for a crystal solar light, as shown and described.

DESCRIPTION

FIG. 1 is a top, right, side perspective view of a first embodiment of a crystal solar light showing my new design; FIG. 2 is a right side elevational view thereof; FIG. 3 is a left side elevational view thereof; FIG. 4 is a front elevational view thereof; FIG. 5 is a rear elevational view thereof; FIG. 6 is a top plan view thereof; FIG. 7 is a bottom plan view thereof; FIG. 8 is a top, left, side perspective view of a second embodiment of a crystal solar light showing my new design; FIG. 9 is a left side elevational view thereof; FIG. 10 is a right side elevational view thereof; FIG. 11 is a front elevational view thereof; FIG. 12 is a rear elevational view thereof; FIG. 13 is a top plan view thereof; and, FIG. 14 is a bottom plan view thereof.

The broken lines shown in the drawings illustrate environmental structure and form no part of the claimed design.

1 Claim, 12 Drawing Sheets
